UNITED STATES PATENT OFFICE.

HENRY SMITH, OF CHICAGO, ILLINOIS.

AWNING.

1,075,385.

Specification of Letters Patent.

Patented Oct. 14, 1913.

Application filed December 11, 1912. Serial No. 736,111.

To all whom it may concern:

Be it known that I, HENRY SMITH, a citizen of the United States, residing at Chicago, in the county of Cook and State of Illinois, have invented certain new and useful Improvements in Awnings, of which the following is a specification, reference being had therein to the accompanying drawing.

My invention relates to awnings and consists in the matters hereinafter described and then pointed out in the appended claims.

In the accompanying drawings Figure 1 is a front view of an awning embodying the features of my invention with the parts in position when the awning is out of use; Fig. 2 is a top plan view of the parts of Fig. 1 in position when the awning is partly extended; Fig. 3 is an end view taken at the right hand of Fig. 2 with the parts in position when the awning is extended or in use; Fig. 4 is a plan view of the parts shown in Fig. 3 with the canvas omitted; Fig. 5 is a top plan view of the parts of Fig. 4 in folded position when the awning is out of use; Fig. 6 is an enlarged detail view partly in section on the line 6—6 of Fig. 5; Fig. 7 is a sectional view on the line 7—7 of Fig. 5; Fig. 8 is an enlarged detail view of the parts at the inner end of one of the arms; Fig. 9 is a detail view partly in section on the line 9—9 of Fig. 8; and Fig. 10 is an inverted plan view of the parts of Fig. 6.

In the drawings the same reference numerals throughout the different views represent the same or corresponding parts, the numeral 21 designating a plate upon which the working parts of the awning are carried in juxtaposition to the structure 22 to which the awning is applied. The awning 23 consists of a suitable length of canvas or other cloth having a front skirt 24 and mounted at its inner end upon a roller 25 supported in suitable brackets 26 fastened to the plate 21, the roller carrying a suitable sprocket wheel 27 at one end operated by a chain 28 from any suitable source to wind and unwind the awning to and from its roller or drum. A pair of folding or jointed arms is employed, one at each end of the canvas and adapted to break or fold inwardly at or near their centers. In the form shown the arms consist of inner and outer sections 29 and 30 respectively suitably jointed together at 31 so that they may break inwardly toward the center of the awning but not outwardly.

The inner end of each section 29 is carried by a suitable bracket comprising a body 32 adapted to be secured to the plate 21 by the bolts 33 or other suitable fastening means, 60 and forwardly and downwardly projecting upper and lower wings 33 and 34 respectively, the wings being set at an obtuse angle to the body as clearly shown in Fig. 8 in order to support the arms in a downwardly inclined position so that when the canvas is unrolled the weight of the arms will cause them to move outwardly and downwardly by gravity carrying the outer end of the canvas with them to its extended position. The 70 wings 33 and 34 carry an adjustable pivot-pin 35 which is pivotally mounted upon the upper wing 33 and is adapted to move forwardly and rearwardly in a longitudinal slot 36 in the lower arm 34. The lower end 75 of the pivot-pin 35 is mounted in an angular plate the upper longitudinal portion 37 of which is wider than the slot 36 in order to rest upon and be carried by the adjacent faces of the wing 34, and the lower downwardly projecting portion or arm 38 extends through the slot 36 below the lower face of the wing 34 where it is provided with a screw-threaded opening to engage a correspondingly threaded adjusting bolt 39 85 mounted to freely revolve in the downwardly projecting end 40 of the wing 34. The bolt 39 is provided with a lock nut 41 on the inner side of the end 40 or with a set nut 42 adjacent the inner face of the downwardly projecting portion 38 of the angular plate, its outer end or head being squared or otherwise suitably shaped to receive a wrench or other tool by which to rotate it. By this construction the lower end of the 90 pivot-pin 35 may be moved along the length of the slot 36 in order to place the pin in position more or less inclined to a vertical plane as by moving it toward or away from the vertical body 32 of the bracket, the ends of the part 37 of the plate being beveled or rounded in order to allow its easy movement upon the wing 34. The inner ends of the arms are pivotally connected to the pins in any suitable manner, and in practice I prefer to make the connection so that the joint 31 of the arms will be offset inwardly or toward the center of the awning with respect to the line of this connection and the outer end of the arm, and also so that the arms 100 may be freely adjusted. For these purposes I provide the construction now to be de-

scribed. The pin 35 carries a pivot plate having a sleeve 43 loosely mounted to turn thereon, the outer or free end of the plate being inwardly curved or offset toward the center of the awning as at 44 and provided at the free end of its offset portion with a vertical body 45 which is provided on its inner face with engaging surfaces such as the inclined radial teeth 46 adapted to be engaged by correspondingly faced teeth 47 on the corresponding body 48 on the inner end of the inner section 29 of the associated arm. The parts 45 and 48 are held in position with their teeth in engagement by means of a bolt 49 passing centrally through these parts and provided at one end with a head 50 and at its other end with a nut 51. By loosening the nut 51 the parts 45 and 48 may be separated to allow the teeth 20 to pass over each other so that the arm may be set at any suitable inclination as shown in full and dotted lines in Fig. 8, it being obvious that it may be locked in any suitable position of adjustment by tightening the 25 nut 51 upon its bolt.

In practice the arms are usually arranged in pairs, one arm of each pair at one end of the associated canvas, and with their joints 31 adapted to break inwardly toward each 30 other as shown in Fig. 2 and to lie up against the plate 21 when the awning is rolled-up out of use as shown in Fig. 1. The outer or free ends of the sections 30 of each pair of arms are provided with a revoluble and detachable connection with the awning-pole or cross-rod 53, for which purpose plates 52 are suitably secured to the pole 53 by screws 54 as shown in Figs. 6 and 10, and the end of each section 30 of the 40 arm is provided with a forwardly projecting ear 55 having a key-hole opening or slot 56 adapted to receive the pintle 57 of one of the plates 52, the pintle being provided with a laterally offset shoulder or projection 45 58 below the lower face of the associated ear 55 and adapted to be drawn up through the slot 56 when aligned therewith to enable the plate 52 to be readily removed from the ear 55. The arrangement and disposition 50 of the slot and shoulder are such that these parts are in alignment to permit removal of the plate 52 when the arms are folded inwardly parallel with the line of the building or structure 22 as shown in Figs. 5 and 6, 55 and the shoulder is adapted to lock under the ear 55 by reason of the partial revolution of the ear 55 upon the plate 52 when the arms are in their extended or projected position shown in Figs. 3 and 10. By this arrangement of parts the ears 55 freely turn upon their associated plates 52 as the arms are swung inwardly or outwardly to their different positions, while the shoulders 58 lock under their ears 55 and prevent accidental displacement of the plates 52 when

the arms are extended. The connection affords easy means to readily assemble and disassemble the arms and plates.

By reference to Fig. 8 it will be observed that the pivot-pin is outwardly inclined toward its top so that the arms are inclined outwardly; by this construction when the canvas is unrolled by suitably rotating its roller 25 the arms will swing downwardly and outwardly by gravity toward their extended position carrying with them the cross-rod 53 to which the outer end of the canvas is attached so that as the roller is revolved to unroll the awning the weight of the arms will tend to extend it to its position of use. By reference to Figs. 2 and 3 it will be observed that the joint 31 is offset toward the center of the awning between the outer end of the arm and the pivot-pin 35 so that as the canvas is rolled up on its roller the joint of the sections of the arm will break inwardly to permit the arms to be drawn to the folded position shown in Figs. 1 and 5 when the canvas is rolled up. The adjustment provided between the arms and plates 44 affords a supplemental adjustment of the arms to any desired inclination when desired in addition to that obtained by the angle of the pivoted connection to the brackets, and also allows the arms to be dropped down to position to hang vertically from the plates when the awning is being set-up or taken down which is a great convenience to the workmen as it obviates the necessity of temporarily holding up the outer ends of the arms while the work is being done.

I claim:—

1. An awning-arm comprising a pair of folding sections, a bracket having upper and lower downwardly projecting wings, an outwardly inclined pivot pin pivotally mounted at its upper end in the upper wing of the bracket, a plate adjustable on the lower wing of the bracket and in which the lower end of the pin is mounted, and a pivotal connection between the pin and the inner end of the inner section of the arm.

2. An awning-arm comprising a pair of folding sections, a bracket having upper and lower downwardly projecting wings, an outwardly inclined pivot pin pivotally mounted at its upper end in the upper wing of the bracket, a plate adjustable on the lower wing of the bracket and in which the lower end of the pin is mounted, and an adjustable connection between the pin and the inner end of the inner section of the arm.

3. An awning-arm comprising a pair of folding sections, a bracket having upper and lower downwardly projecting wings the latter of which has a longitudinal slot, an outwardly inclined pivot pin pivoted at its upper end in the upper wing of the bracket, a plate on the lower wing of the bracket

and in which the lower end of the pin is mounted, an arm on the plate projecting through the slot of the lower wing, an adjusting bolt on the bracket engaging the 5 arm, and a pivotal connection between the pin and the inner end of the inner section of the arm.

4. An awning-arm comprising a pair of folding sections, a bracket having upper and 10 lower downwardly projecting wings the latter of which has a longitudinal slot and a downturned end, an outwardly inclined pivot pin pivoted at its upper end in the upper wing of the bracket, a plate on the 15 lower wing of the bracket and in which the lower end of the pin is mounted, an arm on the plate projecting through the slot of the lower wing, an adjusting bolt in the end of the lower wing of the bracket engaging the 20 arm, and a plate pivoted on the pin and adjustably connected to the inner end of the inner section of the arm.

5. An awning-arm comprising a pair of folding sections, a bracket, a pivot pin adjustably mounted on the bracket and outwardly inclined toward its top end, and a plate pivoted on the pin and adjustably connected to the inner end of the inner section of the arm.

30 6. An awning-arm comprising a pair of folding sections, a bracket, a pivot pin adjustably mounted on the bracket and outwardly inclined toward its top end, a plate pivoted on the pin, and frictional interlocking connections between the plate and the inner end of the inner section of the arm.

7. An awning-arm comprising a pair of folding sections, a bracket, an outwardly inclined adjustable pivot pin on the bracket, 40 and a plate pivoted on the pin and having an offset connection with the inner end of the inner section of the arm.

8. An awning-arm comprising a pair of folding sections, a bracket, an adjustable pivot pin on the bracket outwardly inclined toward its top end, and a plate pivoted on the pin and having an offset body connected to the inner end of the inner section of the arm.

50 9. An awning-arm comprising a pair of folding sections having a key-hole slot in its outer end, a plate resting on the outer

end of the arm and having a projection extending through the slot and registering therewith when the arm is in folded position and out of register therewith when the arm is extended.

10. An awning-arm comprising a pair of folding sections, an ear on the free end of the outer section having a slot, a plate resting on the ear having a pintle in the slot and provided with a lateral shoulder to lock under the ear when the plate is rotated thereon.

11. An awning comprising a suitable 65 length of canvas connected at its inner end to a roller and at its outer end to a cross-bar, and an opposite pair of folding arms pivoted at their inner ends and rotatably connected at their free ends to said cross-bar by a detachable joint and adapted to fold inwardly and unfold outwardly when the canvas is rolled and unrolled respectively by its roller.

12. An awning comprising a suitable 75 length of canvas connected at its inner end to a roller and at its outer end to a cross-bar, an opposite pair of folding arms having inwardly offset pivoted inner ends and rotatably connected at their free ends to said 80 cross-bar by a detachable joint, and means to adjust the arms vertically.

13. An awning comprising a suitable length of canvas connected at its inner end to a roller and at its outer end to a cross-bar, and an opposite pair of jointed arms 85 adjustably pivoted at their inner ends and rotatably connected at their free ends to said cross-bar by a separable pin and slot connection and having their joints inwardly offset from the line of their pivots and outer ends.

14. An awning-arm having an ear at its end provided with a slot, and a plate having a pintle provided with a shoulder adapted 95 to be passed through the slot and to dislodge therewith when the ear is turned on the plate.

In testimony whereof I affix my signature in presence of two witnesses.

HENRY SMITH.
